Application March 10, 1939, Serial No. 260,916

10 Claims.

(Cl. 105—190)

The invention relates to railway rolling stock and more particularly to truck structure for use in passenger train vehicles.

The main object of the invention is to prevent rolling of the vehicle body to one side, or from side to side, due either to centrifugal forces exerted upon the vehicle body when the vehicle is rounding curved track, or due to other forces tending to tilt the body transversely of the track.

Stabilizers to prevent such rolling movement have been used previously in railway trucks, the stabilizers consisting of torque rods journaled on the truck frame and having arms at each end engaging the end portions of the truck bolster to keep the bolster in parallel relation with the truck frame at all times. Otherwise during application of an overturning load, the bolster spring on the side of the truck which receives such a load would compress while the bolster spring on the other side would be relieved of some of its load, thereby tilting the bolster relative to the truck frame in a manner that tends to roll the car body a greater amount than when such stabilizers are used. If the truck is designed for lateral motion of the bolster relative to the frame, it is necessary to make provision in the stabilizer mechanism for such relative movement. The present invention provides a stabilizing mechanism which will increase the stability of the car body as compared to the stability obtained with previous arrangements.

Another object of the invention is to provide means for tilting the bolster upwardly on the side of the truck toward which the bolster moves during lateral movement, and further, to provide a stabilizing mechanism extending transversely of the truck, which tilting means and mechanism will counteract the overturning effect of lateral forces transmitted to the bolster from the car body and thereby reduce to a minimum the amount of the car body roll in the direction of the application of the lateral forces.

Another object of the present invention is to provide in a truck of the type with bolster springs mounted on swing hangers, stabilizing mechanism which keeps the bolster and bolster spring seats in parallel relation at all times without interfering with the lateral movement of the bolster relative to the truck frame.

Another object of the invention is to provide a stabilizing mechanism utilizing levers extending transversely of the truck frame to effect the stabilizer action and to fulcrum these levers on that portion of the truck structure which moves laterally of the frame.

Another object of the invention is to utilize the stabilizing levers as means for spacing the truck springs and thereby eliminate the necessity of a spring plank extending across the truck, although some forms of the invention may include a spring plank as part of the truck structure.

Another object of the invention is to effect satisfactory use of coil springs for supporting a lateral motion bolster in railway truck structure, which is provided with a stabilizing mechanism between the bolster and the bolster spring seats, without foregoing the advantages usually attributed to the heavier and more expensive elliptic spring in general use.

These and other detail objects of the invention are attained in the accompanying drawings in which—

Figure 1 is a top view of a four wheel truck with lateral motion bolster and embodying a stabilizer structure. A portion of the bolster is eliminated at one side of the truck to more clearly illustrate the parts beneath the bolster.

Figure 2 is in part a side elevation of the truck and in part a longitudinal section and is taken on the line 2—2 of Figure 1.

Figure 3 is a vertical transverse section taken on the line 3—3 of Figure 1.

Figure 4 is a detail transverse section taken on the line 4—4 of Figure 3.

Figure 5 corresponds generally to Figure 3, but shows the parts in the position assumed when the bolster is at the extreme of one of its lateral movements. The figure also indicates one side of the truck frame lowered due to the application of an overturning load and the forces tending to move the bolster laterally as illustrated.

Figure 6 corresponds generally to Figure 3 but shows the truck springs compressed to a substantially greater extent than in Figure 3 and illustrates the movement of the stabilizing levers during such compression of the bolster springs.

Figure 7 is in part a top view and in part a horizontal section through a bolster and associated frame structure embodying another form of the invention.

Figure 8 is a vertical section through the structure shown in Figure 7 and is taken approximately on the line 8—8 of Figure 7.

Figure 9 is a detail transverse section on the line 9—9 of Figure 8.

Figure 10 is a side elevation of a truck embodying another form of the invention.

Figure 11 is a top view of the bolster and associated structure illustrated in Figure 10.

Figure 12 is a vertical transverse section taken on the line 12-12 of Figure 11.

Figure 13 is a detail vertical section taken on the line 13-13 of Figure 12.

Figure 14 is a top view of the central portion of a truck embodying another form of the invention utilizing a double bolster and duplicate sets of stabilizers.

Figure 15 is in part a side elevation and in part a longitudinal section taken on the line 15-15 of Figure 14.

Figure 16 is a vertical transverse section, taken on the line 16-16 of Figure 14.

The truck shown in Figures 1 to 6 includes the usual wheels 1, axles 2, journal boxes 3, longitudinal equalizers 4, carried on the boxes, equalizer springs 5, and a truck frame preferably consisting of a one piece casting and including wheel pieces 6 with depending pedestal legs 7, receiving journal boxes 3 between them, transverse transoms 8, end rails 9 and other elements not specified in detail. Swing hangers 10 are pivotally suspended from the end portions of transoms 8 by pins 11 and the lower ends of hangers 10 at each side of the truck support cross bars 12. All of the above mentioned parts are of familiar construction.

Cross stabilizers 13 and 14 extend between bars 12, the outer end of each stabilizer resting upon one of the bars 12 and the inner ends of the stabilizers being pivotally connected by vertical links 15 and pins 16. Each stabilizer is of triangular shape, viewed from above, with its wide outer end forming a seat S for one of the elliptic bolster springs 17.

A truck bolster 18 of inverted U shape is carried by springs 17 and its side walls include depending lugs 19 intermediate the center of the bolster and hanger bars 12. Each stabilizer 13 and 14 is fulcrumed on a pair of lugs 19 by a pin 20. Preferably, spring seats S are fitted with rubber pads 21 and rubber pads 22 mount the bolster on springs 17. The outer ends of the bolster are provided with rubber pads 23 disposed to abut the inner faces of wheel pieces 6 to limit the lateral movement of the bolster when hangers 10 swing on their pivots. The vehicle body bolster 24 (Fig. 3) is carried upon the truck bolster center plate 25 in the usual manner. The usual spring planks are eliminated. All of the load is carried from the bolster through its springs 17 directly to the swing hanger cross bars 12 except when overturning forces are transmitted from the bolster through the stabilizers 13-14 to the bolster spring seat.

The bolster and bolster spring may swing as a unit with the hangers, just as similar parts have functioned in previous trucks with swing bolsters, but any tendency of the bolster to tilt vertically, due to the presence of forces which normally would act unequally on the bolster springs, is prevented by stabilizers 13-14. A force tending to raise or lower one end of the bolster, such as an overturning load, will be distributed through the stabilizers 13-14 to the bolster spring seat on that side of the truck to which the force is applied and then through the bar 12, swing hangers 8 and frame 6 to the equalizer springs 5, without changing the parallel relation of the bolster and bolster spring seats. There is a tendency to keep the bolster level except for such tilting as may result from inclination of

the track or unequal compression of equalizer springs 5 at opposite sides of the truck, as indicated in Figure 5 which shows hangers 10 compressed more than the right-hand spring 5 as indicated by dimension lines A and A+. During relative lateral movement of the bolster 18 and truck frame as also indicated in Fig. 5, the right-hand cross bar 12 is lowered, while the left-hand cross bar is raised and the stabilizers 13-14 do not permit the left-hand bolster springs 17 to compress more than the right-hand bolster springs, and this also tends to keep the bolster level or to prevent tilting of the bolster in the wrong direction. These conditions result in a minimum amount of car body roll and provide greater stability than is obtained with previous constructions, particularly those having springs under the bolster and which permit a different amount of deflection of the bolster springs on one side of the truck than on the other.

Figures 7, 8 and 9 illustrate a form of the invention embodying a truck frame 35, with supporting parts similar to those shown in Figures 1 to 6, and a bolster 36 corresponding generally to the bolster of the structure shown in Figures 1 to 6. The cross stabilizers 37 and 38 are pivoted at 39 and 40, respectively, to depending brackets 41 on the bolster. The inner ends of the stabilizers are pivotally interconnected by links L and pins 42. The outer end of each stabilizer rests upon a cross bar 43, extending between swing hangers 44 suspended at 45 from the truck frame. A spring seat 46 is pivotally supported by the outer portion of each stabilizer immediately over its supporting cross bar 43, and coil springs 47 carried by seats 46, support the end portions of bolster 36.

Preferably, each end of the bolster includes an outwardly and downwardly projecting arm 48 extending beneath the frame wheel piece and over the equalizer bar 49. A shock absorber 34 of familiar telescoping type is pivotally connected at its opposite ends to the outer end of arm 48 and to a bracket 35a projecting from the wheel piece.

Stabilizers 37 and 38 function similarly to the stabilizers previously described to prevent unequal action of springs 47 without interfering with the free lateral movement of the bolster relative to the frame. The intermediate portion of the bolster is box shaped in cross section (see Fig. 9) and the end portions are widened and open downwardly and are provided with circular pockets to receive the coil springs.

Shock absorbers 34 are added because of the tendency of coil springs to oscillate more freely than elliptic springs rendering a dampening device desirable to prevent unnecessary vibrations or vertical oscillations of the bolster and car body because of the easy action of the coil springs. It will be understood that the stabilizing feature may be retained independently of the shock absorber or other spring dampening structure.

Figures 10, 11, 12 and 13 illustrate another form of the invention in which the cross stabilizer levers 80 and 80' are supported intermediate their ends upon the cross bars 81, carried by swing hangers 82, pivotally suspended from the truck frame 83. The inner ends of stabilizers 80 and 80' and pivotally connected to each other through a block 84 pinned to one stabilizer and positioned in a jaw on the other stabilizer. The assembly preferably includes rubber insulating elements 85

bonded to the block 84 and the adjacent portions of the stabilizer jaw, which permits the necessary relative movement of the levers 80 and 80' transversely of the truck by the shear action of the rubber. The outer ends of stabilizers 80 and 80' are pivotally connected directly to arms 86 projecting outwardly and downwardly from the bolster 81. A shock absorber 88 connects the outer ends of each bolster and stabilizer and the adjacent sides of the truck frame. Coil springs 89 are seated upon stabilizers 80 and 80' and support the bolster.

The stabilizers fulcrum on the cross bars 81 and any force tending to compress one spring 89 and tilt the corresponding stabilizer is transmitted to the other stabilizer and the opposite end of the bolster to equalize the spring movements and maintain equal distances between the bolster and the swing hanger cross bars 81.

Figures 14, 15 and 16 illustrate a form of the invention embodying a wide or double bolster and a duplicate set of cross stabilizers. The truck frame 90 is supported by coil springs 91 mounted on equalizers 92 extending between the axle journal boxes 93. Swing hangers 94 are pivotally suspended at 95 from the frame and each of their cross bars 96 pivotally supports the outer ends of two spaced stabilizers 97, which are individually fulcrumed at 98 upon brackets 99 depending from the sides of bolster 100. The inner end of each stabilizer 97 is linked to the inner end of the stabilizer at the other side of the truck. The outer end of each stabilizer mounts a seat 101 for a bolster coil spring 102 received in a cap 100a.

Tie rods 103 limit the expansion of springs 102 when there is no load on the bolster and enable the bolster springs and stabilizers to be handled as a unit when not assembled with the rest of the truck structure. Preferably, shock absorbers 104 are connected at their upper ends to the bolster and at their lower ends to cross bars 96 and dampen the vertical oscillations of springs 102.

The stabilizers function in a manner corresponding to those illustrated in Figures 7, 8 and 9, but each pair of stabilizers functions substantially independently of the other pair and due to the extent of the bolster longitudinally of the truck and the support of the same at its corners by springs 102, spaced longitudinally of the truck, the stabilizers do not interfere with the bolster tilting longitudinally of the truck. During such tilting action one pair of stabilizers would shift relative to the other pair of stabilizers but the ends of each side of the bolster would be raised or lowered equally to avoid undesirable tilting of the bolster transversely of the truck.

The tilting of the bolster in a vertical plane relative to the truck frame during lateral movement is characteristic of all of the structures described irrespective of the details of construction, and the stabilizers in all forms of the invention tend to distribute the vertical loads to the bolster springs on both sides of the truck.

In all forms of the invention the upwardly tilting action of the bolster on the side of the truck toward which the bolster moves during lateral movement, together with the stabilizer mechanism, counteracts the overturning effect of lateral forces transmitted to the bolster from the car body, and thereby reduces to a minimum the amount of car body roll in the direction of lateral movement.

In all forms of the invention, the bolster springs on both sides of the truck are kept under substantially equal load or deflection when rounding

curves so that the side of the vehicle body at the outside of the curve is lifted and the side of the car body at the inside of the curve is lowered, thus tending to prevent tilting or rolling of the car body toward the outside of the curve and increasing the easy riding qualities of the vehicle. The stabilizer mechanism is pivotally mounted on the bolster. The bolster and bolster springs may be adapted for the stabilizer structure irrespective of the truck frame or other parts of the truck structure, such as the equalizer bars, or any part of the vehicle body carried by the truck.

The general stabilizer arrangement is also adapted for trucks utilizing a spring plank in which case the stabilizers may be fulcrumed or pivotally connected to the spring plank and such construction, originally disclosed in the present application, is illustrated and described in divisional application filed July 30, 1941, Serial No. 404,600.

It will be understood that the use of rubber cushioning elements is not limited to the specific points illustrated and described but may be included wherever desired to prevent metal to metal contact and to deaden noise and absorb some road shocks and also to compensate for the angling of various parts with which the rubber elements are associated. Ordinarily, thick rubber cushions cannot be used for spring seats because the springs would tip over due to lateral forces carried through the spring from bolster to spring seat or vice versa, and this would be particularly true where elliptic springs are used.

In the forms of the invention utilizing bolster elliptic springs, a spring on one side of the truck can be easily applied or removed from the truck by clamping the spring on the other side of the truck and raising the car body sufficiently to allow the spring to clear its spring seat.

The spring on the other side, due to the stabilizing levers, will raise both ends of the bolster to facilitate the removal of the first spring. Old arrangements require direct lifting of the bolster on the same side as the spring to be removed.

While the use of telescoping shock absorbers is indicated in some of the structures, it will be understood that these may be omitted altogether or that other dampening devices may be included in any form of the invention.

While some forms of the invention illustrate bolsters of box-shaped cross section and other forms of the invention show bolsters of inverted U or trough-shaped cross section, it will be understood that these sections are illustrative and that any desired type of bolster may be adapted for mounting the cross stabilizers.

The construction may be changed substantially in various other ways without departing from the spirit of the invention and the exclusive use of such modifications of the invention as come within the scope of the claims is contemplated.

What is claimed is:

1. In a railway truck, a frame, swing hangers suspended therefrom, respective springs at opposite sides of the truck supported by said hangers, a bolster mounted on said springs, levers for stabilizing the action of said springs extending inwardly from said swing hangers and each separately pivoted on said bolster at a point spaced from the center of the bolster and extending beyond its pivot to connect with the opposite stabilizer lever.
2. In a railway truck, a frame, support members carried by said frame at opposite sides of

15

the truck and movable transversely of the frame, individual springs on said support members, a bolster carried on said springs, levers mounted on said members and extending inwardly therefrom and pivotally connected to each other at their inner ends and being fulcrumed on said bolster intermediate their interconnection and said members and stabilizing the action of said springs.

3. In a railway truck, a frame, a bolster movable laterally of the truck relatively to said frame, bolster carrying springs, levers beneath said bolster and disposed end to end transversely of the truck with their inner ends pivotally connected to each other and with portions spaced from said ends pivotally connected to said bolster, and means pivotally suspended from said frame and pivotally connected to said levers and supporting said spring and bolster through said levers.

4. In a railway truck, a frame, a pair of swing hangers suspended from each side of said frame, a cross bar carried by each pair of swing hangers, a lever pivotally connected to and extending inwardly of the truck from each of said cross bars and with its inner end pivotally anchored to the lever connected to the other cross bar, a spring seat mounted on each of said levers, springs on said seats, a bolster extending across the truck and carried on said springs, there being a pivotal connection between each of said levers and said bolster whereby said levers equalize the movement of said springs at the opposite ends of said bolster.

5. A railway truck as described in claim 4 in which the levers extend outwardly beyond their associated cross bars, there being shock absorbers connecting the truck frame and the outer ends of said levers.

6. In a railway truck, a frame, hangers pivotally suspended from said frame to swing transversely of the truck, and structure supported by said hangers and movable transversely of the truck by the swinging of said hangers on their pivots, said structure including spring seats, individual springs thereon, a bolster on said springs and stabilizer levers extending transversely of said frame, the inner ends of said levers being secured to each other and portions of said levers spaced from their inner ends having connections respectively to said bolster and to other parts of said structure, said connections preventing relative vertical movement of the connected parts at the points of connection, the structure being so constructed and arranged as to provide equal vertical deflection of said springs at opposite sides of the truck and to maintain the bolster in parallel relation with said spring seats irrespective of overturning forces applied to the bolster and irrespective of movement of said structure transversely of the truck on said hangers, each stabi-

lizer lever extending from the central portion of the truck outwardly and being connected between its ends to the bolster and having its outer portion carried by the swing hangers.

5 7. A railway truck as described in claim 4 which also includes shock absorbers at the sides of the truck each having telescoping members connected respectively to the truck frame and to a part supported from the corresponding swing hanger,

10 the latter-mentioned member of each shock absorber being connected to the corresponding member of the other shock absorber by the stabilizing levers.

8. In a railway truck, a truck frame, swing hanger structure suspended from the sides of said frame, a lever pivotally connected to and extending inwardly of the truck from each of said structures and having its inner end pivotally anchored to the lever connected to the other structure, a spring seat on each of said levers, springs on said seats, a bolster extending across the truck and supported on said springs, there being a pivotal connection between each of said levers and said bolster whereby said levers equalize the movement of said springs at the opposite sides of the truck.

15 9. A railway truck as described in claim 8 in which the bolster extends outwardly beyond its supporting springs, there being shock absorbers connecting the truck frame and the outer ends of said bolster.

10 10. In a railway truck, a frame, hangers pivotally suspended from said frame to swing transversely of the truck, and structure supported by 35 said hangers and movable transversely of the truck by the swinging of said hangers on their pivots, said structure including spring seats, individual springs thereon, a bolster on said springs and stabilizer levers extending transversely of said frame, the inner ends of said levers being secured to each other and portions of said levers spaced from their inner ends having connections respectively to said bolster and to other parts of said structure, said connections preventing 40 relative vertical movement of the connected parts at the points of connection, the structure being so constructed and arranged as to provide equal vertical deflection of said springs at opposite sides of the truck and to maintain the bolster in parallel relation with said spring seats irrespective of overturning forces applied to the bolster and irrespective of movement of said structure transversely of the truck on said hangers, each stabilizer lever extending from the central portion of the truck outwardly and resting on the swing hangers and supporting the bolster 45 springs.
